REGISTERING AND DISPLAYING APPARATUS PARTICULARLY APPLICABLE TO TOTALIZATORS

John Handley, London, England

Application August 29, 1936, Serial No. 98,520
In Great Britain January 3, 1935

2 Claims. (Cl. 235—134)

This invention relates to improvements in registering apparatus for incorporation in totalizer and like equipment, of the type adapted to receive bet signal impulses directly or indirectly from ticket-issuing and like machines and including stepwise-operated primary mechanism.

The present invention provides improved apparatus of the type referred to including a series of register discs each of which, after the first or 10 units register disc, is driven from the preceding register disc by means including a cam driven step wise by the preceding register disc operating mechanism and operatively connected to a toothed wheel of the succeeding register disc operating mechanism whereby to impart a step of 15 rotation to said toothed wheel in the final step of rotation of said cam.

Registering apparatus constructed in accordance with the present invention is illustrated in 20 the accompanying drawings in which Fig. 1 is a rear elevation, Fig. 2 a part plan part horizontal section and Fig. 3 a fragmentary elevation drawn to a larger scale of the transfer mechanism which interconnects one register disc with a succeeding 25 register disc.

The registering apparatus shown includes an electro-magnet 1 (Fig. 1) which receives electrical bet-representing impulses to be counted and which imparts oscillatory movements to an armature lever 2 attraction of which to the electro-magnet 30 1 is opposed by a pair of springs such as indicated at 6. The armature lever 2 carries a pawl 4 adapted, in the return vibrations of the armature lever 2 under the action of the springs 6, to impart stepwise uni-directional rotation to a ratchet wheel 5, reverse rotation of which is prevented 35 by a detent 5'. The ratchet wheel 5 transmits rotation to a spur wheel 9 through accumulator mechanism forming the subject of my co-pending application Serial Number 98,519, filed August 29, 40 1936.

Each impulse transmitted by the spur wheel 9 to a rotary digit-displaying disc 17 geared thereto counts unity, digits 1-9 and 0 being equi-spaced circularly on the front face of the disc 17 which is rotated through one-tenth of a revolution for each transmitted impulse, so as to exhibit a digit. The digit disc 17 and its associated driving mechanism constitutes a first or single 50 units indicating apparatus.

A digit is exhibited by the disc 17 when said digit registers with a window in a front panel (not shown) of the apparatus.

The first or single units register disc may be 55 actuated by two such driving mechanisms as described, the spur wheels 9 of said mechanisms meshing with pinions 12, 12^a, respectively, (Fig. 2).

These pinions rotate freely on the fixed shaft 60 3. Integral with the pinion 12^a and rotating about

the same shaft 3 is a bevel gear 7 which forms part of the differential gearing 13. The other parts of the differential gearing are the bevel gears 8, 10 and 11. Gear 8 is integral with pinion 12 and rotates with it about the shaft 3. The 5 gears 10 and 11 are mounted on a disc 33 which is joined to the gear wheel 14 and rotates with it about the shaft 34 which joins the pinion 12 to the bevel gear 8. Locknuts 35 and 36 keep the various gears in their proper spatial relationship. It will thus be seen that impulses received by the pinions 12 and 12^a will be transmitted independently of one another to the gear wheel 14. For example an impulse received by pinion 12^a will be transmitted to the gear 7 and 15 cause the conjoint rotation of pinion 12^a and gear 7. Rotation of the gear 7 will cause rotation of gears 10 and 11 which will roll over the surface of gear 8 without causing it to rotate. The rolling 20 of gears 10 and 11 on the surface of gear 8 will rotate disc 33 and impart an equal amount of rotation to the interconnected gear 14. Rotation of the pinion 12 will produce identical results but in this case the gears 10 and 11 roll over the gear 7 without causing it to rotate.

Rotation of the gear wheel 14 will rotate the gear wheel 15 with which it meshes. The gear wheel 15 is integral with the shaft 37 which is free to rotate on the spindle 16. Integral with one end of the shaft 37 is a dog-clutch element 113 which 25 cooperates and meshes with a mating dog-clutch element 112 which is provided with a rectangular groove, and which is slidably mounted on shaft 16. A tongue 38 which is rigidly fixed to the shaft 16 is partially inserted in this groove and 30 serves to transmit rotary motion directly from the clutch element 112 to the shaft 16. Likewise, rotary motion received by the gear wheel 15 will be transmitted directly to the shaft 16 by means of the intermeshed clutch elements 112 and 113. 35 The dog-clutch elements may be disengaged by moving the element 112 away from the element 113 and thereby causing the tongue 38 to be projected more deeply into the groove in the element 112. When the clutch members are completely 40 disengaged the spindle 16 will be free to rotate without being checked by the mechanism which actuates gear 15 and normally prevents the spindle from rotating independently.

In order to disengage the clutch members the 50 register is provided with a rotatable shaft 39 which is situated below and at right angles to the spindle 16. The shaft is provided at one end with a weighted lever 82 which is rigidly attached to the shaft. Lifting of the lever 82 will cause rotation of the shaft 39. Rigidly attached to the shaft 39 are a number of flat plates 40 on each of which is mounted a pair of spaced pegs 41. The lip 42 on the clutch member 112 extends into 55 this space between the pegs. The pegs are also 60 60

so situated on the plates 40 that rotation of the shaft 39 by lifting the lever 82 will cause the pegs to move toward the axis of the shaft 39. As the pegs move toward this axis they will carry with them the lip 42 and will ultimately cause the clutch member 112 to be withdrawn completely from the clutch member 113. Reversal of the rotation of the shaft 39 will of course cause the clutch members to be re-engaged.

10 The spindle 16 is provided at one end with a digit disc 17 which is rotated one-tenth of a revolution for each impulse received.

15 On its end remote from the digit disc 17 the spindle 16 carries a snail cam 18 (Fig. 3) engaged by a follower 107 on a lever 19 urged by a spring 20 in the direction to keep the follower 107 in engagement with the cam 18. The lever 19 is pivoted between its ends at 108 and has pivoted on its end remote from the follower 107 a link 20 109 presenting a pin 21 adapted to impart step-wise rotation to a toothed wheel 22 which is freely rotatable on shaft 16^a but which is selectively connected through clutch 112, 113 with shaft 16^a to drive a register disc 110 similar to and 25 partially overlapping the units digit disc 17. The movement of the pin 21 into and out of engagement with the toothed wheel 22 is controlled by a reciprocating guide link 24 one end of which presents an arcuate guide slot 23 in which works 30 the pin 21. The other end of the guide link 24 is connected by the pin 25 to one arm of a U-shaped member 111 which oscillates about the shaft 43. The other arm of the member 111 is connected by the link 26 to pin 27 which is mounted 35 on the snail cam 18. Consequently rotation of the cam 18 will cause reciprocatory motion of the guide link 24. As viewed in Fig. 3, the cam 18 rotates counter-clockwise. As the follower 107 rises under the action of the cam 18 the spring 40 20 is stretched and the pin 21 is constrained, under the combined control of the cam 18 and the guide link 24, to vacate an interdental space and to enter a succeeding interdental space of the toothed wheel 22. When the peak of the cam 18 45 passes beyond the follower 107 the follower drops into the root 18^a of the cam under the action of the spring 20 on the lever 19, which latter is thus forcibly rocked and imparts a step of rotation equal to one-tenth of a revolution to the toothed 50 wheel 22 through the medium of the link 109 and the pin 21. A pair of detent pins 30 on the guide link 24 co-operate with the toothed wheel 22 in order positively to lock the latter during the intervals between successive steps of rotation of the toothed wheel 22. As will be understood from an examination of Figure 3, with cam 18 being driven by shaft 16 in a counterclockwise direction, pins 30 will be moved about a tooth of wheel 22, and pin 21 operating in guide slot 23 will not 55 engage wheel 22. Pins 30 will be moved to the right as viewed in Figure 3 until the pin 27 on cam 18 reaches a position in a line horizontal with the shaft 16. Continued rotation of cam 18 in a counterclockwise direction will cause pins 60 30 to move to the left and this movement will continue until the pin 27 on cam 18 assumes a position at the left of shaft 16 and in a position substantially horizontal with respect to shaft 16. During this movement pins 30 will be moved 65 completely free of wheel 22 and pin 21 will be moved into a position between two teeth of wheel 22. At the time when pin 27 is in a horizontal position with respect to shaft 16 and to the left thereof, follower 107 and cam 18 are in such a 70 75 position that follower 117 may be operated by a

spring 20, to assume the zero position with the follower 107 in the root 18^a of the cam, as the follower moves over the peak point of cam 18, to thus cause pin 21 to rotate wheel 22 as desired. Upon further rotation of cam 18, the pin 27 will now be moved toward the right, pin 21 will be moved out of engagement with wheel 22 and pins 30 will consequently be moved to a position to engage wheel 22 to thus hold wheel 22 in its new position until the above cycle is repeated. 32 denotes 10 a guard plate secured on the shaft 16 and adapted to guard or shield the projecting end of the follower pin 31 as the follower 107 drops over the peak and into the root of the cam 18. When the cam 18 is in the angular setting in which 15 its root depression 18^a is engaged by the follower 107 the zero digit is exhibited by the disc 17. The pin 27 carries a roller 28 which co-operates in the rotation of the pin with a circular group of electric contacts 29 (Fig. 2) adapted to control a large remotely disposed public indicator. Mechanism similar to the transfer mechanism connecting the shaft 16 of the units register disc with the shaft 16^a of the tens register disc is 20 interposed between the shaft 16^a and the shaft 16^b of a hundreds register disc, and is repeated for each subsequent register disc required. All of the register discs are zeroized simultaneously by raising a weighted master lever 82, upward rocking movement of which effects withdrawal together of dog-clutch elements 112 splined one on each shaft 16, 16^a, 16^b etc., from driving relation with mating dog-clutch elements 113 which normally transmit the drive to the digit discs 17, 110, etc., through the medium of the 30 dog-clutch elements 112. When the digit discs are thus de-clutched from their respective drives the action of the spring-pressed levers 19 on the snail cams 18 rotates said cams with their shafts and digit discs in a clockwise direction until the 40 cams come to rest with their root depressions 18^a engaged by the associated followers 107 on the levers 19, in which angular settings of the cams the digit discs exhibit their zero digits. During the zero setting movement of any one group of 45 parts 19, 21, 24, etc., the associated wheel 22 of the succeeding register disc is held by pins 30 but this has no effect upon the register disc associated with the wheel 22 due to the declutched position of the clutch 112 and 113. 50

I claim:

1. A mechanism for transferring stepwise impulses from a register disc of lower order to one of higher order, which comprises a cam rotated by said register disc of lower order, a toothed wheel capable of rotating said register disc of a higher order, a spring-pressed lever actuated by said cam and linked to a pin engageable with the toothed wheel, a reciprocating guide link, said pin being also under the control of said reciprocating guide link, means for actuating said reciprocating guide link concurrently with the cam, the conjoint effect of the spring-pressed lever and the reciprocating guide link being such as to impart a stepwise rotation to said toothed wheel to rotate the register disc of higher order when the register disc of lower order has been rotated a predetermined amount. 55

2. A mechanism as claimed in claim 1 in which the reciprocating guide link carries detent means for preventing the rotation of the toothed wheel during the intervals between the successive steps of rotation of said toothed wheel. 60 65 70
